BIRD ANIMAL FIGURE TOY

Arthur J. Stephens, Roswell, N. Mex.

Application March 14, 1950, Serial No. 149,505

4 Claims. (Cl. 46—107)

1

My invention relates to a mechanical toy. A primary object of the invention is to provide a wheeled pull toy which embodies a novel and highly simplified mechanism, driven by the wheels, and connected with movable parts of figures for imparting life-like motion to the figures.

A further object of the invention is to provide a wheeled pull toy having a plurality of separate figures mounted thereon, and including movable parts which are actuated so that the figures will simulate a live flock of chickens, or the like.

A further object is to provide a toy of the above mentioned character which will be highly amusing to children, and which is highly simplified, compact, sturdy and durable in construction and attractive in appearance.

Other objects and advantages of the invention will be apparent during the course of the following description.

In the accompanying drawings, forming a part of this application, and in which like numerals are employed to designate like parts throughout the same,

Figure 1 is a side elevational view of a wheeled pull toy embodying my invention, part in section,

Figure 2 is a plan view of the toy, parts broken away,

Figure 3 is a bottom plan view of the toy, part broken away, and parts in section,

Figure 4 is a central vertical longitudinal sectional view taken on line 4—4 of Figure 2, and,

Figure 5 is a transverse vertical sectional view taken on line 5—5 of Figure 4.

In the drawings, where for the purpose of illustration is shown a preferred embodiment of my invention, the numeral 10 designates a flat horizontally elongated rectangular platform which is longitudinally elongated, as shown. The platform 10 has rigidly secured to its bottom side laterally oppositely disposed depending bearing blocks 11 and 12, which are arranged near and rearwardly of the longitudinal center of the platform 10. Suitable aligned bearings 13 are secured to the bottom of the blocks 11 and 12, and a transverse horizontal axle or shaft 14 is journaled within the bearings 13, and extend across the platform 10 and is spaced from the bottom of the platform, as shown. The axle or shaft 14 is provided near its longitudinal center, and near the transverse center of the platform 10 with an eccentric portion or crank 15, integral therewith. Wheels 16 are secured to the opposite ends of the axle or shaft 14, for rotation therewith, and these wheels are preferably arranged substantially adjacent to the opposite sides of the platform 10.

Suitably rigidly secured to the top of the platform 10 are a plurality of spaced upstanding vertical pegs or posts 17, and the pegs 17 are

2

preferably arranged in staggered relation, as shown clearly in Figures 1 and 2. Fixedly secured to the tops of the pegs 17 are relatively stationary blocks or body portions 18, which are shaped to simulate the bodies of chickens. As best shown in Figures 1 and 2, the blocks 18 are relatively narrow, and somewhat elongated longitudinally. The blocks 18 are preferably disposed in parallel relation, as shown, and the blocks assume the spaced staggered relationship of the pegs 17 which support them. Each block 18 is provided in its forward end and bottom with a recess 19, and each block has a transverse pivot pin 20 mounted upon its forward end and extending through the recess 19. Pivotally mounted upon each pin 20 is a vertically swingable elongated curved member or neck 21, shaped to simulate the neck of a live chicken or the like, and provided at its forward end with a head 22 which likewise simulates the head of a chicken or the like.

The necks 21 extend longitudinally forwardly of the blocks or body portions 18, and the rear portions of the necks 21 are disposed within the recesses 19, and substantially concealed therein. The necks 21 are freely swingable vertically, and tend to remain in depending or lowered positions, under the influence of gravity, wherein the tips of the heads 22 contact the top of the platform 10, Figure 4. The rear ends of the necks 21 are preferably provided with narrow arcuate grooves 23, which receive and guide the upper portions of flexible elements for cords 24. The tops ends of the cords 24 are permanently securely anchored within openings formed in the tops of the necks 21, within the recesses 19, as shown at 25. The cords 24 pass about the rear ends of the necks 21, rearwardly of the pivot pins 20 and downwardly through the bottoms of the recesses 19. Small openings 26 are formed in the horizontal platform 10 substantially directly below the recesses 18, and the cords 24 pass through these small openings, as shown in Figures 3 and 4. The arrangement is such that when the cords 24 are pulled downwardly through the openings 26, that the necks 21 and heads 22 are elevated or swung upwardly. When the cords 24 are released, so that they may pass upwardly through the small openings 26, the necks 21 will again descend due to gravity. This mode of operation is continuous, as the toy travels forwardly, as will be more fully explained, and the action of the necks 21 simulates the well-known pecking movement of chickens in a life-like manner.

Longitudinally forwardly of the group of blocks 18 and pegs 17, and substantially at the transverse center of the platform 10, the same has rigidly secured to its bottom side a depending bearing block 27, provided with a vertical opening or bore 28 which registers with an opening 29 formed

in the platform 10 above the block 27. A vertical pin or peg 30 is journaled within the openings or bores 28 and 29, and the top end of the peg 30 extends above the top of the platform, while its bottom end projects below the block 27, Figure 4. A block or rooster body portion 31 is rigidly secured to the top of the peg 30, for rotation therewith, and a short tubular spacer 32 surrounds the peg 30 between the bottom of the block 31 and the top of the platform 10. This spacer 32 contacts the bottom of the block 31 to hold the block and peg against downward movement. The block or rooster portion 31 is provided in its forward and bottom with a slot or recess 33, similar to the recess 19. A transverse pivot pin 34 is mounted upon the forward end of the block 31 and extends across the recess 33, as shown. An elongated curved neck 35 has its rear end pivotally mounted upon the pin 34 and disposed within the recess 33, and the neck 35 is provided at its forward end with an extension or head 36, which simulates the head of a live rooster. The neck 35 like the necks 21 is freely swingable vertically, and tends to remain in the lowered position, Figure 4, due to gravity. The rear end of the neck 35 is preferably provided with an arcuate groove 37, for receiving and guiding a flexible element or cord 38, similar to the cords 24. The top end of the cord 38 is permanently anchored within a small opening 39, formed in the top of the neck 35. As shown in Figure 4, the cord 38 passes about the rear end of the neck 35 and downwardly through the bottom of the recess 33, and rearwardly of the pivot pin 34. The platform 10 is provided slightly rearwardly of the peg 30 with a small opening 40, slidably receiving the cord 38 therein. The cord 38 and all of the cords 24 extend below the platform 10, as shown.

Near and forwardly of the rear end of the platform 10, the same has rigidly mounted upon its bottom side a depending tubular guide or bearing 41, disposed near the transverse center of the platform. A similar depending guide or bearing 43 is rigidly secured to the bottom of the platform 10 adjacent to one side of the bearing block 27, and near the forward end of the platform. The guides 41 and 43 are arranged in axial alignment, and an elongated horizontal straight reciprocating bar or rod 44 is slidably supported within the bearings 41 and 43 and adapted to reciprocate longitudinally therein. The elongated rod 44 is substantially parallel to the longitudinal center line of the platform 10, as shown, and this rod extends throughout the major portion of the length of the platform and longitudinally forwardly and rearwardly of the bearings 43 and 41 respectively, Figure 3. A suitable longitudinally extending connecting rod 45 is arranged beneath the rod 44, and is provided at its rear end with a loop or eye 46, pivotally receiving the crank 15 therein. Tubular spacers 47 and 48 are mounted upon the crank 15, upon opposite sides of the loop 46, Figure 3, and these spacers serve to maintain the connecting rod 45 centered beneath the rod 44. The connecting rod 45 further includes a forward upwardly inclined bifurcated extension 49, pivotally connected as at 50 with the reciprocating rod 44 longitudinally forwardly of the axle 14.

A short horizontally swingable arm 51 is rigidly secured to the bottom end of the pin or peg 30, and disposed beneath the bearing block 27. The outer end of the arm 51 is pivotally connected as at 52 with a longitudinal connecting rod or

link 53, formed of wire or the like, and the rear end of this link 53 is pivotally connected as at 54 with the bifurcated extension 49 of the connecting rod 45. The link 53 lies adjacent to one side of and below the reciprocating rod 44.

The bottom end of the flexible element or cord 38 is permanently secured or tied to the rear end of the link 53, adjacent to the bifurcated extension 49, as shown at 55. The cords 24 of the forwardmost pair of necks 21 are tied or secured together, and passed through a small transverse opening 56 formed in the reciprocating rod 44 near its longitudinal center. The cords 24 of the rearmost pair of necks 21 are secured or tied together below the reciprocating rod 44, as at 57, and a short longitudinally extending cord or flexible element 58 connects the rearmost pair of cords 24 with the reciprocating rod 44 forwardly of the rear bearing 41, as at 59. The cord 24 of the centrally located intermediate neck 21, shown in cross section in Figure 4, is also tied or secured to the rod 44 at 59. The other intermediate neck 21, arranged adjacent to one side of the platform 10, Figure 2, has its cord 24 secured or tied with a small transverse opening of the rod 44, at a point longitudinally forwardly of the loop 59, as shown at 60.

A suitable handle 61 is secured to the forward end of the platform 10 at the transverse center of the platform, and this handle is employed for pulling the wheeled toy over the floor or the like.

So that trash or other objects will not become entangled in the working mechanism below the platform 10, I provide a bottom casing or cover 62, which is suitably rigidly secured to the bottom of the platform 10, and substantially completely enclosing all of the mechanism below the platform. The casing 62 preferably extends for the entire length of the platform 10, and the sides 63 of the casing are disposed laterally inwardly of the wheels 16 and provided with openings for rotatably receiving the axle 14. Adjacent to the axle 14, the casing 62 is provided in its bottom with a rectangular opening 64 to provide clearance for the rotation of the crank 15 and connecting rod 45.

The operation of the toy is as follows:

The toy is pulled over the floor or ground by means of the handle 61. This causes the wheels 16 to rotate, rotating the crank 15. This causes the connecting rod 45 to oscillate, for reciprocating the elongated rod 44. Each time the connecting rod 45 is shifted longitudinally forwardly and rearwardly, the horizontal arm 51 swings forwardly and rearwardly and turns the vertical peg or pin 30. This causes the block 31 to swing horizontally from right to left, above the platform 10. This swinging movement of the block 31 will be continuous, as long as the toy is pulled by the handle 61. The blocks 18 do not swing, but are fixedly secured to the pegs 17, as previously stated.

The arrangement is such that each time that the reciprocating rod 44 is shifted longitudinally forwardly, the cords 24 of all of the necks 21 except the neck of the central intermediate chicken, shown in section in Figure 4, are tensioned for raising the necks 21. When the rod 44 is shifted longitudinally forwardly, the cord 24 of the central intermediate neck 21 is slackened, as is the cord 38. Accordingly, when the rod 44 is in the forward position the neck 35 and the central intermediate neck 21 will remain in their lowered positions. When the rod 44 shifts longitudinally rearwardly, the cord 24 of

the central intermediate neck 21 is tensioned, as is the cord 38, and the necks connected with these cords are elevated, while the remainder of the necks 21 remain lowered. This operation is continuous, as long as the toy is pulled forwardly by the handle 61, and the action of the necks 21 and 35 simulates the movement of a flock of chickens or the like while pecking at feed or grain.

The construction of the toy is highly simplified, compact, sturdy and durable. The various parts of the toy, such as the blocks 18 and 31, necks 21 and platform 10 are well adapted to be formed of wood, or some suitable plastics material. However, any suitable material may be employed which is light and sufficiently strong and durable. The blocks 18 and necks 21 and 35 may be decorated or colored as desired, and although I have shown the blocks 18 and 31 shaped like chickens, if desired, the figures could be shaped to represent other fowl, such as ducks, geese or the like. If desired, the figures could be also shaped to represent some small animal.

It is to be understood that the form of the invention herewith shown and described is to be taken as a preferred example of the same, and that various changes in shape, size and arrangement of parts may be resorted to, without departing from the spirit of the invention or the scope of the subjoined claims.

Having thus described my invention, I claim:

1. A pull toy comprising a substantially horizontal wheeled platform, a crank element arranged beneath the platform and connected with the wheels for rotation therewith, a group of separate spaced upstanding pegs mounted upon the top of the platform and projecting above the same, bird simulating blocks secured to the tops of the pegs, vertically swingable necks pivotally connected with the blocks and extending longitudinally of the blocks, the platform having a plurality of small openings, a forward substantially vertical rotatable peg journaled upon the platform near its forward end and extending above and below the platform, a bird simulating block secured to the top end of the rotatable peg, a vertically swingable neck pivotally secured to the last named block, a substantially horizontal arm secured to the bottom of the rotatable peg and disposed below the platform, longitudinally spaced aligned bearings secured to the bottom of the platform near the opposite ends of the platform, a longitudinal elongated reciprocatory rod journaled within the bearings and spaced near and below the platform, flexible elements connected with the vertically swingable necks of all of the blocks and extending through the small openings of the platform and connected with the reciprocatory rod below the platform, a connecting rod arranged beneath the reciprocatory rod and having its forward end pivotally connected with the reciprocatory rod and its rear end pivotally connected with the crank element, and a link connecting the connecting rod and said horizontal arm of the rotatable peg.

2. A pull toy comprising a substantially horizontal wheeled platform, an eccentric crank element connected with the wheels and disposed below the platform and adapted to be driven by the wheels, a handle secured to one end of the platform for pulling it, a substantially vertical pin journaled upon the platform for rotation and extending above and below the platform, a bird

simulating member secured to the top of the pin and including a vertically swingable neck, the platform having a small opening, a flexible element connected with the vertically swingable neck and extending through the small opening of the platform and below the platform, a horizontal arm secured to the bottom of the substantially vertical pin for rotation therewith and disposed beneath the platform and spaced from the crank element, guide means secured to the bottom of the platform, a longitudinally shiftable member connected with the guide means and disposed beneath the platform and connected with the crank element to be driven thereby, the flexible element being connected with the longitudinally shiftable member, and a link connecting the substantially horizontal arm and longitudinally shiftable member, the arrangement being such that rotation of the wheels and crank element causes the bird simulating member to swing horizontally above the platform while the neck swings vertically:

3. A bird animal figure toy comprising a horizontal wheeled platform, a crank element arranged beneath the platform and connected with the wheels for rotation therewith, a group of separate spaced upstanding pegs mounted upon the top of the platform and projecting above the same, bird simulating blocks secured to the tops of the pegs, vertically swingable necks pivotally connected with the blocks and extending longitudinally of the blocks, a longitudinal elongated reciprocatory rod positioned below and spaced from said platform and dependingly supported from the latter, flexible elements connecting the vertically swingable necks of all of said blocks to said reciprocatory rod, and a connecting rod arranged beneath the reciprocatory rod and having its forward end pivotally connected with the reciprocatory rod and its rear end pivotally connected to said crank element.

4. A bird animal figure toy comprising a horizontal wheeled platform, a crank element arranged beneath the platform and connected with the wheels for rotation therewith, a vertical rotatable peg positioned near the forward end of said platform and extending above and below the latter, a bird simulating block secured to the top end of the rotatable peg, a vertically swingable neck pivotally secured to said block, a substantially horizontal arm secured to the bottom of the rotatable peg and disposed below the platform, a longitudinal elongated reciprocatory rod positioned below and spaced from said platform and dependingly supported from the latter, a flexible element connecting the vertical swingable neck to the reciprocatory rod, a connecting rod arranged beneath the reciprocatory rod and having its forward end pivotally connected with the reciprocatory rod and its rear end pivotally connected with the crank element, and a link connecting the connecting rod and said horizontal arm of the rotatable peg.

ARTHUR J. STEPHENS.
